UNITED STATES PATENT OFFICE.

EDWARD A. RICHARDSON, OF MANSFIELD, MASSACHUSETTS.

SPORTING SHOE.

Application filed April 20, 1926. Serial No. 103,269.

This invention relates to an improved shoe worn more particularly by contestants in athletic sports, and has for its object to provide a shoe of this character that is worn more particularly by runners and in which a stiffening metal plate is inserted between the inner and outer soles thereof, the plate having anti-slipping spurs or projecting members arranged to extend out through openings in the outer sole, the plate being slotted longitudinally preferably at its middle portion to permit the outer sole to be fastened through this plate to the inner sole by sewing or by other suitable fastening means.

With these and other objects in view, the invention consists of certain novel features of construction, as will be more fully described, and particularly pointed out in the appended claims.

In the accompanying drawings:

Figure 1 is a bottom view showing a portion of a shoe with my improved stiffening plate, shown in dotted lines, as being inserted between the inner and outer soles thereof.

Figure 2 is a central sectional elevation through the shoe showing the inner and outer soles as stitched together through the slot in the plate.

Figure 3 is a perspective view of my improved stiffening plate showing the central longitudinal slot therein and a plurality of spurs riveted to the metal plate.

Figure 4 is a sectional elevation through one of the spurs detached.

In the building of athletic shoes, particularly those worn by runners in athletic contests, it is found of advantage to insert a stiffening metal plate between the inner and outer soles thereof and this plate is provided with a plurality of spurs extending out through the outer sole as an anti-slipping means; also, it is found of advantage to be able to sew the outer sole to the inner sole along its middle portion and to permit this to be done I have slit the plate longitudinally for a portion of its length and through which the stitches may be passed without being interfered with by the plate; also if desired other fastening means may be passed through this slot; and the following is a detailed description of the present embodiment of my invention and showing one

means by which these advantageous results may be accomplished:

With reference to the drawings, 10 designates the thin metal plate which is formed in outline somewhat in the shape of the shoe tap but somewhat smaller in size and to this thin metal plate I secure by rivets or otherwise a plurality of spaced apart spurs 11 about its marginal edge leaving a central portion 13 of the plate free.

Through this central portion I form a slot 14 which extends longitudinally of the plate and beginning preferably from its rear edge 15 and extending for a substantial portion of the length of the plate.

When this plate is inserted between the inner sole 16 and the outer sole 17 its spurs 11 extend outwardly through corresponding openings or holes formed in the outer sole and this outer sole is then secured to the inner sole, preferably by a sewing operation about its outer edge. Also, it is found in shoes of this character of advantage to sew the two soles together through the middle portion thereof as at 18, which sewing or fastening operation is permitted by the slot 14 formed through it and through which the stitches pass, the sewing being extended from the rear of the plate towards the front or toe of the shoe to or beyond its middle portion, the slot 14 in the plate being of a length to permit such sewing operation.

I do not wish to be restricted to fastening the inner and outer soles together through this slot 14 in the plate by sewing, as other fastening means may be employed if desired.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a sporting shoe, an inner sole, an outer sole, a metal plate secured intermediate said soles, spurs secured to the outer surface of the plate about its margin and extending out through openings in the outer sole and said plate having a narrow longitudinal slot extending from its rear edge forwardly for a portion of its length.

2. In a sporting shoe, an inner sole, an outer sole, a flexible metal plate secured between said soles, a plurality of spurs secured to the outer surface of said plate about its marginal edge and extending outwardly through openings in the outer sole, the middle portion of said plate being provided with an elongated longitudinally disposed relatively narrow slot extending from its rear edge a distance at least half the length of the plate through which said soles may be secured together. ¹⁰

In testimony whereof I affix my signature.

EDWARD A. RICHARDSON.
